(57) **CLAIM**

The ornamental design for an abdominal wrap, as shown and described.

DESCRIPTION

FIG. 1 is a perspective view of an abdominal wrap shown in use.

FIG. 2 a top plan view of the abdominal wrap shown in FIG. 1.

FIG. 3 is a bottom plan view of the abdominal wrap shown in FIG. 1.

FIG. 4 is a first side elevational view of the abdominal wrap shown in FIG. 1.

FIG. 5 is a second side elevational view of the abdominal wrap shown in FIG. 1.

FIG. 6 is a first end elevational view of the abdominal wrap shown in FIG. 1; and,

FIG. 7 is a second end elevational view of the abdominal wrap shown in FIG. 1.

The broken lines in FIG. 1 showing a human figure illustrate an environmental structure which forms no part of the claimed design.

It is understood that the broken lines shown within the claimed design indicates stitch lines which form part of the claimed design.
